CONVERTIBLE PRINTING PRESS

William Ward Davidson, Evanston, Ill.

Application July 25, 1940, Serial No. 347,454

10 Claims. (Cl. 101—142)

The present invention is a continuation in part of my copending application, Serial No. 293,554, filed September 6, 1939, and relates to printing presses generally, and more particularly to presses which are convertible to perform different printing processes. The disclosure made in the above copending application is hereby incorporated and made a part of the present application.

Three common classes of printing processes are: lithographic, intaglio, and type printing. With more and greater uses being made of commercial printing of these various types, it is important that presses be constructed and designed for rapid and easy conversion.

In order, however, to provide convertible printing presses, the question of interchangeability of printing media and the question of inking and ink distribution are important problems. In the present invention, I provide an improved convertible press wherein the blanket and type segment are preferably interchangeable upon one cylinder, and the lithographic plate of another cylinder is utilized as an ink conveying or transferring surface in the train of rollers that are employed to supply the type segment with ink. My invention is illustrated herein as incorporated in a three cylinder press.

Another purpose of the invention is to provide a press that may be converted to perform different classes of printing processes without need for changing the inking mechanism of the press.

Another purpose of the invention is to provide a convertible press which is characterized by a minimum number of alterations that are needed to convert the press, and the rapidity with which the conversion may be accomplished.

Moreover, I provide a convertible press having the above characteristics, that prints the paper upon the same side, preferably the top side, whether converted to one form or the other, thereby minimizing the necessity for changing the position or operation of associated parts, such as the feed and the delivery mechanisms.

Other objects will become apparent from the drawing, the description relating thereto and the appended claims.

Referring now to the drawing:

Fig. 1 illustrates a three cylinder rotary press set up for offset lithographic printing;

Fig. 2 illustrates the press shown in Fig. 1 as converted for direct type printing;

Fig. 3 shows a fragment of the plate cylinder when constructed to use a spacer beneath the plate; and

Fig. 4 is a view corresponding to Fig. 3 but showing a resilient ink distributing surface substituted for the plate and spacer.

Broadly speaking, without changing the inking characteristics of the inking unit or its position, I convert the blanket cylinder of an offset lithographic couple into a lithographic or type cylinder and utilize the plate on the plate cylinder of the couple as one of the rollers in the train of rollers employed for inking the type upon the printing cylinder.

In Figs. 1 and 2, a three cylinder press is shown, wherein conversion from the offset lithography shown in Fig. 1 to the direct printing in Fig. 2, is accomplished by replacing the etched plate with an unetched plate. Form rollers, preferably surfaced with a resilient material, are then added to convey ink placed upon the unetched plate to the type upon the printing cylinder and an eccentric means is employed to lift the cylinder enough to clear the type.

More particularly, in Figs. 1 and 2, the blanket cylinder of a three cylinder lithographic press is shown at 10, intermediate the platen 11 and plate cylinder 12. Blanks of paper 13 are fed from the conveyor board 14 by the feed rollers 15 which are synchronized to feed a sheet to the bite of the cylinders between the platen 11 and blanket 10. A leading overlap of the sheet is preferably provided at the gap 16 so that the stripper 17 may be tilted, if desired, into the gap to catch the leading edge of the sheet and direct it onto the delivery table 18.

The ink applying rollers are indicated at 20 and comprise the fountain roller 21, the ductor roller 22, the distributor roller 23 and the ink form rollers 24. The form rollers 24 are pivotally mounted to run in contact with the distributing roller 23 constantly by arms 25 mounted for movement about the shaft supporting the distributing roller 23. In this way, if there is any variation in the distance desired or required between the distributing roller 23 and the plate cylinder 12, it can be allowed for or taken up by relative movement of the form rollers 24, toward or away from each other, in the space afforded between the distributing roller and the plate cylinder.

The water damping mechanism comprises the fountain roller 26, the water ductor roller 27, the water distributing roller 28 and the water form roller 29. The form rollers 24 and 29 may be lifted separately to clear the plate whenever desired by suitable hand or automatically operated cams (not shown).

The plate 30 is shown mounted upon the plate cylinder 12 as clamped at the leading edge 31 and drawn taut over the bed 32 by a tensioning clamp device 33 disposed at the trailing edge thereof.

I prefer to mount the cylinder 12 so that its center of rotation is slightly eccentric to pivotal supports in the side frames so that it may be moved towards and away from the blanket cylinder 10. In the particular construction shown, the cylinder 12 rotates upon a shaft whose bearing circumference is indicated by the numeral 40 and the shaft is provided with integral eccentric end studs 41, that are journaled in the side frames. A plate 42 is keyed to one of the studs 41 at the outer ends thereof and has fastened thereto a throw arm 43 which is held in either one of two positions as shown by a spring press shot bolt 44. The arm 43 is shown in its lowered position in Fig. 1 where it rests against an adjustable stop 45 as held there resiliently by a spring 46. In Fig. 2, the arm is shown in its upper position as supported by the shot bolt 44, after the arm 43 has been raised manually and the shot bolt inserted under the end thereof. When in its lowered position, the arm 43 moves the shaft 40 to hold the cylinder 12 against the blanket cylinder 10 with the required blanket inking pressure, and when in its raised position, the arm 43 rotates the shaft 40 to lift the cylinder 12 enough to clear the type segment 39 upon the cylinder 10.

Whether the arm 43 and the cylinder 12 are disposed in their upper position or in their lower position, the ink rollers 24 accommodate for the relative displacement present between the roller 21 and distributing roller 23. The rollers 24 remain in contact with the plate by moving closer towards each other to fill the space between the distributing roller and the plate if the space is increased, or separate to accommodate themselves to the space if the space is decreased.

Whenever it is desirable to convert the embodiment illustrated in Fig. 1 into a direct or type printing press, the blanket 34, shown in Fig. 1, is removed from the blanket cylinder 10 and a cast type plate 35, or the like, is secured to the cylinder 10. The plate 30, in Fig. 2, then becomes a distributing surface for the ink supplied thereto by the rollers 24 which hitherto served as form rollers. The plate 30 may be the same plate without any etching solution supplied thereto, or a different plate which has not been etched. In either event, the water form roller 29 is raised so that it will not contact the plate.

In order to transfer the ink from the plate 30, I prefer to employ two pairs of rollers 36 and 37, preferably surfaced with resilient material, which serve as distributing and form rollers respectively, for the type segment 35. The diameter of these rolls are preferably the same, although not necessarily so, whereby they may be used interchangeably in their respective positions without danger of one roller being confused with the others by persons operating the press who are unskilled mechanically.

Thus, when the conversion is made from lithography to direct or letter type printing, whether the form in Fig. 1 is considered the initial construction of the press which is adapted to be converted for direct printing, or whether the form in Fig. 2 is considered the initial construction adapted to be converted to offset lithographic printing, the conversion may be had readily and

quite easily by persons comparatively unskilled with printing presses. The inking mechanism remains physically unchanged. The shot bolt 44 is retracted and the arm 43 located at the desired point. The segments upon cylinder 10 are interchanged, the rollers 36 and 37 are added or removed as required, preferably through inclined slots (not shown) in the side frames, the water form roller 29 is raised or lowered as desired, 10 and the form damping roller 29 is raised. No other changes are needed to convert the press from one form of printing to another and in either case the blank sheets are printed on the same side which, in this instance, is upon the 15 upper side.

It will be appreciated that cylinders 10 and 12 are preferably gear driven relative to each other and the relative drive may be maintained through a conventional Oldham coupling (not shown).

Furthermore, I prefer to mount the platen 11 so that it will be thrown out whenever a sheet is skipped by the feed and whether a cast type segment upon the cylinder 10 or other means for direct printing is used in the conversion, the working diameter in the cylinder construction is determined in relation to the pitch line of the gear teeth of the two coupled cylinders so that other forms may be substituted for the blanket 25 in the conversion without altering the operations of the printing couple.

In event it is not desired to separate the plate and blanket cylinders, it will be appreciated that within the object of not having two metal ink 35 distributing surfaces running against each other, the plate cylinder may be machined to a smaller radius to receive a resilient or composition ink distributing covering 47 (Fig. 4) in substitution for the plate which is thick enough to bring the surface thereof up to the pitch line of the gears. With this arrangement the plate 30, when mounted on the plate cylinder, is provided with a spacer 48 (Fig. 3) beneath it to bring the radius 40 thereof up to the pitch line of the gear teeth on the cylinder.

Having described certain embodiments of the invention and disclosed the manner in which they are believed to function and operate in their best and preferred form, it will be apparent to those skilled in the art, that various uses, modifications, and changes may be made therein without departing from the spirit and substance of the invention, the scope of which is commensurate with the appended claims.

What is claimed is:

1. A combination offset lithographic and direct printing press comprising cooperating lithographic, platen, and blanket surfaces, means interchangeable with the blanket surface to provide a direct printing surface, means for varying the distance between the blanket surface and the lithographic surface, an inking mechanism, and means for using the lithographic surface as an ink form surface to transfer ink from the inking mechanism to the direct printing surface including removable rollers disposed between the lithographic surface and the direct printing surface.

2. A convertible printing press comprising a plurality of cooperating cylinders, interchangeable blanket and direct printing surfaces for one of the cylinders, a platen surface upon another cylinder running in contact with the first cylinder to provide a printing couple, a plate, means for varying the distance between the plate and

the blanket surface to provide a clearance therebetween, and means for transferring ink from the plate to the direct printing surface without direct contact between the plate and the direct printing surface.

3. A convertible printing press comprising a cylinder having a blanket surface disposed above a platen, a plate surface cooperating with the blanket surface for the transfer of ink, means for inking the plate surface, means interchangeable with said blanket surface for providing a direct printing surface and means for converting the plate surface into an ink distributing surface including a removable form roller receiving ink from the plate surface and running in contact with said direct printing surface.

4. A convertible press comprising a lithographic cylinder, a platen cylinder, a blanket cylinder, means interchangeable with the blanket on said blanket cylinder for providing a direct printing surface, an inking mechanism adapted to supply ink to the lithographic cylinder, and means for converting the lithographic cylinder into an ink distributing cylinder to supply ink to the direct printing surface when the press is doing direct printing.

5. A convertible printing press comprising a cylinder having a blanket surface disposed above a platen, a plate surface cooperating with the blanket surface for the transfer of ink, means for inking the plate surface, means for converting the plate surface into an ink form surface, and means interchangeable with said blanket surface for providing a direct printing surface.

6. A printing press comprising a lithographic surface, a platen surface and a blanket surface being capable of engaging both the lithographic surface and the platen surface, and means for converting the press from an offset lithographic to a direct printing press by interchanging a direct impression printing surface with a blanket surface and by interchanging an ink form surface for the lithographic surface, and a single inking mechanism supplying ink to the ink form surface or the lithographic surface depending upon which surface is in use.

7. A printing press comprising a lithographic surface, a platen, a blanket cylinder running in

contact with said lithographic surface and platen, inking means for the lithographic surface, means for converting the blanket cylinder into a direct impression cylinder, and means for converting the lithographic surface into an ink form surface for transferring ink from the inking means to the direct impression cylinder.

8. A convertible printing press comprising a blanket cylinder and a platen, a blanket for the cylinder, a second cylinder having a bed surface, a plate for the bed surface, a composition covering interchangeable with the plate, means for establishing a substantially constant printing radius for both the plate and the covering, a direct printing segment interchangeable with the blanket, and inking means in contact with either the plate or the covering, whichever is on the plate receiving cylinder.

9. A convertible printing press comprising a platen and a cylinder having a blanket surface, a plate surface adapted to run against the blanket surface, means for inking the plate surface, means interchangeable with said blanket surface for providing a direct printing surface, means for varying the distance between the blanket surface and the plate surface to provide a clearance therebetween, and means for converting the plate surface into an ink distributing surface including a pair of ink transfer rollers one of which contacts the ink distributing surface and the other contacting the direct printing surface.

10. A convertible printing press comprising a platen cylinder and a cylinder provided with interchangeable blanket and direct printing surfaces, a third cylinder provided with a bed, means for supporting a plate on the bed including a spacer, an inking mechanism adapted to engage and transfer ink directly to the plate on the third cylinder, and means for converting said third cylinder into an ink distributing surface by removing the plate and spacer and substituting a resilient ink transfer covering whereby ink is transferred from the inking mechanism to the ink distributing surface on the third cylinder and thence to the direct printing surface when the press is doing direct printing.

WILLIAM WARD DAVIDSON.
